UNITED STATES PATENT OFFICE.

WILLIAM H. MILLSPAUGH, OF SANDUSKY, OHIO.

SUCTION-ROLL.

994,863.

Specification of Letters Patent. Patented June 13, 1911.

Application filed April 8, 1909. Serial No. 488,739.

To all whom it may concern:

Be it known that I, WILLIAM H. MILLSPAUGH, a citizen of the United States, residing at Sandusky, in the county of Erie and 5 State of Ohio, have invented certain new and useful Improvements in Suction-Rolls; and I do hereby declare the following to be a full, clear, and exact description of the invention, such as will enable others skilled 10 in the art to which it appertains to make and use the same.

The object of this invention is to provide a revolving suction-roll for use in paper and pulp mills or elsewhere that shall be simple 15 and practical, highly efficient in operation, and yet cheap to manufacture.

In the use of suction-rolls with paper-making machines, success depends upon proper control of the pressure of contact 20 between the suction-box and interior surface of the revolving perforated shell or cylinder. As explained in the specification of my U. S. Patent No. 895,283, there must be constant air-tight contact between the 25 box and shell, while at the same time the bearing-pressure must be limited to such degree as will prevent the box from becoming locked to the shell under influence of the suction or vacuum, otherwise there would 30 be injury to both the shell and packing, rapidly destroying them, and greater time would be required to operate the device. The lack of provision for limiting the pressure of contact has made it necessary to 35 apply only a moderate degree of suction in the rolls known or in use prior to the invention disclosed in said patent.

In all prior suction-rolls having provision for maintaining the box and interior surface 40 of the cylinder in air-tight contact, or causing one to bear against the other independently of the attractive force of suction, the direction of relative movement has been radial; as in the case of the machine exhibited 45 in my above mentioned patent, wherein the box is radially adjustable in the cylinder-heads, and by means of springs the box and interior surface of the cylinder are maintained in contact under yieldable pressure. 50 In that machine, I have provided for limiting the pressure of contact by means of adjusting screws, one on each cylinder-head, operating in effect as stops between the cyl-

inder or the cylinder-bearings and the box in opposition to the force supplied by the 55 springs; and, as the bearing-pressure is yieldable, it is controlled instantly and exactly by the said screws, which serve for making all necessary adjustments. My present invention involves the same general 60 principle of forcing the box and interior surface of the cylinder in contact and limiting the pressure of such contact, modified however in that the pressure is controlled by relative adjustment in a longitudinal direction. This is effected by having the line 65 of contact between the box and cylinder inclined relative to the line of adjustment, and causing the pressure-applying force to act in the direction of the line of adjustment and opposing such force by stop-means operating between the cylinder and the box to limit the bearing-pressure. Stated differently, either the adjustment is axial and the 70 box and interior surface of the cylinder are 75 in contact at a slant to the axis of the cylinder, *i. e.*, the cylinder is interiorly tapered or conoidal and the open face of the box correspondingly inclined to fit thereto; or else the reverse conditions exist, *i. e.*, the 80 cylinder is interiorly cylindrical, while the direction of adjustment is at a similar slant to the axial, the guides for the relative longitudinal motion of the box being arranged accordingly. The effect in either instance 85 is to give a relative radial adjustment, though there is or need be no actual radial adjustment.

It will be obvious that the alternative arrangements above mentioned may be combined in one construction; that is, the cylinder may be tapered so that the line of contact between the box and cylinder will be on a slant to the axis, while the line of relative longitudinal adjustment may be on 95 a reverse slant to the axis; the effect of which would be to give a quicker adjustment. While I do not consider this arrangement as practical as the others, it is mentioned as within the scope of my invention. 100

The main advantages in the construction and operation of a suction-roll on the foregoing principle are simplification in structure, practicality of manufacture, and the fact that the bearing-pressure between the 105 box and cylinder can be controlled and all

adjustments made by a single adjusting screw at one end of the cylinder, the said screw being conveniently located for the operator at the front of the machine. I do not, however, confine myself to the use of a single adjusting screw in all cases.

In the present suction-roll, I have also embodied provision for angular adjustment of the box in the cylinder, in order that the 10 box may be set at the desired position to adapt it to the line of travel of the wire or felt of the paper machine, or of the sheet of paper, it being understood that the web will in some machines pass over the top of 15 the roll and in others at one side of the roll, or even at the bottom.

The accompanying drawings, which are to be taken as a part of this specification, 20 illustrate several embodiments of my invention, which may also be embodied in other forms while the details of construction and arrangement of parts may be variously modified. Without restricting myself, therefore, to any particular construction, the 25 invention will be described with reference to the drawings and then more particularly pointed out and defined in the appended claims.

Figure 1 of said drawings is a longitudinal vertical section of a suction-roll embodying my invention, in which embodiment the perforated revolving shell or cylinder is interiorly tapered or conical. Fig. 2 is a front end elevation thereof. Fig. 3 is a detail view of one end of the cylinder and box, in longitudinal vertical section, showing a modification in the pressure-controlling means. Fig. 4 is a longitudinal vertical section, with parts in elevation, of another 40 form of suction-roll embodying my invention, in which the shell or cylinder is interiorly cylindrical, while the guides for the box are on a slant to the axis and consequently on a slant to the interior surface of the cylinder. Fig. 5 is a longitudinal vertical section of another form of suction-roll embodying my invention, in which the cylinder is the actually adjustable member instead of the box as in the preceding figures. Fig. 6 is a longitudinal vertical section through one end of the cylinder illustrating a modification of Fig. 5.

In the several figures of the drawings, A denotes the revolving foraminous shell or cylinder; B the standards or pillow-blocks; and C the suction-box arranged longitudinally within the cylinder.

K is a gear for driving the cylinder from a pinion and is shown affixed on the cylinder between two members of the rear standard.

The standards B are or may be bolted to the rails X of the paper-making machine, a removable piece Y being interposed between the rail and standard at the front end

in order to allow for putting on and taking off the wire or felt, or other web which passes around the cylinder.

It is understood that the open top of the box conforms to the interior curvature of the cylinder to fit closely thereagainst, and is provided with suitable packing ϵ which may be hard or yielding. In use, the suction-box is generally provided with longitudinally adjustable packing-heads for the purpose of extending and shortening the operative length of the box in accordance with the width of paper being made or treated; but as this feature is independent of my present invention, I have simply shown the 80 box provided with fixed end packing-strips. It is also understood that the box communicates by suitable means with a suction-pump or exhaust apparatus. In the illustration, I have shown the box provided with tubular 85 end portions D, constructed lower than the medial open-topped portion of the box which alone bears against the interior surface of the cylinder; and one or both of said ends D is or are adapted for coupling to 90 pipe-connections with the said pump or exhaust apparatus.

In Figs. 1 and 2, the shell or cylinder A is 95 interiorly tapered or conical, and the contacting open face of the box is correspondingly inclined to the axis of the cylinder. This inclination of the open face of the box may be provided in several ways, as by inclining the box itself, or forming the longitudinal packing-strips with inclined bottoms, or inclining the grooves which hold the packing; the specific means being immaterial to the principle of the invention. The direction of inclination is preferably inward toward the rear end of the cylinder, that is, 100 the interior diameter of the cylinder diminishes from its front toward its rear end. The box is longitudinally adjustable in or relative to the cylinder, and for this purpose its end-portions D are supported and guided by heads E, which are rigidly affixed to and may be integral with the cylinder-bearings. In this instance, I have shown the heads angularly adjustable to permit setting the 110 box at different angular positions in the cylinder. For this purpose, the heads are fitted in the openings in the standards B beyond the bush-linings of the cylinder-bearings, so that the heads may be turned co-axially with the cylinder, and they are 115 adjustably secured to the standards in any suitable manner. The heads may be circular, but in the present case they are shown in the form of cross-bars having arcuate or sector-shaped ends fitted in the standards or pillow-blocks, and provided with flanges overlapping the outer faces of the standards or pillow-blocks and adjustably secured thereto by bolts or set-screws inserted 120 through segmental slots in the said flanges, 125

as shown in Fig. 2. Tapped holes may be provided in the face of the standard to receive the bolts or set-screws for a wider range of angularity. Two of such tapped holes are shown in Fig. 2, one at the top and one at the bottom.

The particular form of guides between the heads and box is of course a matter of mechanical preference. In the illustration, I 10 show the heads E formed with gibs or guide-flanges e working in lateral ways or grooves d in the end portions of the box. The direction of adjustment is or may be axial; the guides e d being parallel with the axis of 15 the cylinder; though, as it has already been suggested, this is not essential to the fundamental principle of the invention, since the direction of adjustment may be inclined to the axis at a reverse slant to the line of contact between the box and shell.

The direction of the interior taper of the cylinder being as indicated, the box is forced longitudinally rearward to maintain its bearing-pressure against the interior surface 25 of the cylinder, its movement in that direction being limited to control the pressure of contact. For this purpose, an adjusting screw or bolt J is inserted loosely through the front head or member E, and is 30 tapped or threaded into a lug F on the bottom of the suction-box. A coiled expansion spring H placed on the screw between the head E and lug F, yieldingly forces the box rearward until the head of the screw or 35 bolt engages the member E, thus limiting the relative movement. In other words, the spring forces the box and interior surface of the cylinder in yieldable contact, and the screw limits the pressure of such contact. By 40 adjusting the screw, the pressure of contact can be controlled to the exact degree desired; the spring being contracted as the screw is adjusted inward, or turned in a direction to draw the box forward, and being allowed to 45 distend as the screw is adjusted in the opposite direction. By means of a common wrench, all adjustments necessary may thus be made with the single screw J at the front of the suction-roll.

50 It will be evident that the spring or other pressure applying means may be arranged at one end and the limiting-means at the opposite end of the suction-roll. For example, at the larger end of the cylinder, a spring 55 may be arranged between the box and an arm rising from the cylinder-bearing or standard; while an adjusting screw may be tapped through a similar arm on the standard or bearing at the opposite end and bear 60 against the box in opposition to the force of said spring. Should this arrangement be adopted, it would be preferable to reverse the taper of the cylinder, that is, have its interior diameter decreased toward its front 65 end, and place the spring at the rear end

and the adjusting screw at the front for the better convenience of the operator.

As the direction of relative adjustment is longitudinal, it will also be evident that the bearing-pressure between the box and interior surface of the cylinder may be controlled by a single adjusting screw, as well where the whole adjustment is positive as where yielding bearing-pressure is maintained. Fig. 3 shows a construction having 70 positive adjustment. Said construction is similar to that shown in Fig. 1, except that the spring is omitted, and the screw J is susceptible of a rotary motion only, being prevented from sliding or moving end wise 75 by the bolt-head j and a collar j' on the screw abutting against opposite sides of the head E through which the screw is inserted. Hence the adjustment of the screw determines the bearing-pressure of the box 80 against the interior surface of the cylinder.

In Fig. 4, I have shown an embodiment of my invention wherein the interior surface of the shell A is cylindrical, and the line of adjustment of the box is at a slant 90 to the axis of the cylinder, which is accomplished by inclining the guides e d between the heads E and end-portions of the box, in accordance with the slant of the line of adjustment; the adjusting screw J 95 being similarly inclined. The guides may be either in alinement, or they may be parallel but not in alinement, as shown. Except as above described, the construction shown in Fig. 4 is substantially similar to 100 that shown in Fig. 1, and no further description will be necessary.

In Figs. 1 to 4 inclusive, the cylinder-bearings are supposed to be fixed and the box free for endwise adjustment. But it is 105 obvious that the arrangement may be reversed, that is the box C may be the actually stationary member, and the shell or cylinder A the adjustable member. For example, without any modification in any of 110 the foregoing structures, the box C may be so coupled with rigid pipe-connections as to maintain the box in fixed position, while the standards B may be allowed to slide or shift in a longitudinal direction; or the 115 cylinder bearings may be shiftable in the standards; in which event the guides and adjusting devices would operate with precisely the same effect as hereinbefore set forth.

I have illustrated in Figs. 5 and 6 other embodiments of my invention, involving the reverse mode of adjustment in a construction where the box is fixed relative to the cylinder-bearings, and the cylinder is shiftable longitudinally in its bearings. In these embodiments, the shell is interiorly tapered and the box axially adjustable and inclined to fit the interior taper of the shell, 120 as in the case of Figs. 1 to 3, but the em- 125

bodiments about to be described are equally adapted for the use of an interiorly cylindrical shell and slanting adjustment, as described with reference to Fig. 4.

5 In Fig. 5, the ends of the box are fastened to and supported by brackets B^1 and B^2 carried by the front and rear standards B. The cylinder A is slidable in its bearings, and two thrust-heads or collars E^1 10 also slidable in said bearings, are arranged to abut against the opposite ends of the cylinder. The heads are rigidly connected by a central rod G, an extension J^1 of which projects forward through an opening in the front bracket B^1 . It is obvious that by means of the connected thrust-heads E^1 , the cylinder may be shifted longitudinally relative to the box. A spring H^1 arranged on J^1 between the bracket B^1 and 15 the front head E^1 forces the cylinder longitudinally in a direction to increase the pressure of contact, the rod J^1 being loose in B^2 , and the movement is limited by the nut j screwed on the end of the rod J^1 , and abutting 20 against the bracket B^1 . The heads E^1 may ride on the end portions of the box and be guided thereby to obviate any tendency of the heads to turn with the cylinder. The gear K may be engaged by a long pinion K^1 25 to accommodate the longitudinal adjustment.

The construction shown in Fig. 6 is the same as in Fig. 5, except in the following particulars: The ends of the cylinder project beyond its bearings and also have bearings on the thrust-heads B^1 , which latter are slidably supported and guided by the end portions of the box, and are connected by a plurality of tie-rods G, one of which 30 provides the extension J^1 for a spring H^1 and limiting-nut j , as shown.

It will be noted that the taper of the shell in Figs. 5 and 6 is in the opposite direction to the taper as shown in Figs. 1 to 45 4. This is because the spring is at the same end, while the shell is the movable member. The effect of moving the shell in the manner shown in Fig. 5 is the same as moving the box in the opposite direction.

While the brackets B^1 and B^2 in Figs. 5 and 6 are shown as permanent attachments to the standards which provide the cylinder-bearings, it is obvious that said brackets 55 might be angularly adjustable for setting the box at different angular positions in the cylinder.

In this specification, the terms, "line of contact" and "line of adjustment", are 60 used for convenience of expression, and will be understood as follows: The "line of contact" denotes any longitudinal line in the cylindrical or conical surface where the cylinder and open face of the suction-box are in contact; and the "line of adjustment"

may be taken as the mean line of actual movement, or any line indicating the direction of relative movement between the box or face of the box and cylinder. The term "cylinder" is intended to include any 70 form of shell which may be used in place of the true cylinder.

In some cases it may be desirable to withhold the suction box from actual contact with the interior surface of the cylinder 75 and depend upon the water or moisture collecting between the box packing and the cylinder to seal or partially seal the vacuum chamber; in any event actual frictional contact may not be necessary if the suction box packing and interior surface of the cylinder are in near contact sufficient to 80 preserve a good working vacuum or suction, as required. These conditions will be understood as meaning "contact" within the 85 sense of the present invention.

I claim as my invention and desire to secure by Letters Patent:

1. A suction-roll having provision for relative longitudinal adjustment between the 90 suction-box and cylinder, and means whereby a relative radial adjustment results.

2. A suction-roll wherein the degree of contact between the suction-box and interior surface of the cylinder is controlled by relative longitudinal adjustment between said members on a line slanting to or non-parallel with the line of contact.

3. A suction-roll having an interiorly tapered cylinder and a suction-box therein 100 with its open face correspondingly inclined and adapted to contact with the interior surface of the cylinder, there being provision for relative longitudinal adjustment for regulating the pressure of contact.

4. A suction-roll having provision for relative longitudinal adjustment between the suction-box and cylinder in a direction slanting to the interior surface of the cylinder with which the suction-box contacts.

5. A suction-roll having provision for relative longitudinal adjustment between the suction-box and cylinder and having guides for the box at a slant to the interior surface of the cylinder.

6. A suction-roll wherein the suction-box and interior surface of the cylinder are maintained in contact with yielding pressure, and longitudinal adjusting means limiting the pressure.

7. A suction-roll having longitudinal adjusting means forcing the suction-box and interior surface of the cylinder in contact at a limited pressure.

8. In a suction-roll, the combination with 125 means forcing the box and interior surface of the cylinder in contact, of a single adjusting instrumentality limiting the pressure of such contact.

9. In a suction-roll, the combination of 130

the cylinder and suction-box in contact with its interior surface, one bearing against the other with yielding pressure, and a single adjusting instrumentality limiting the bearing pressure.

10. A suction-roll having provision for maintaining contact between the suction-box and interior surface of the cylinder by longitudinal adjustment of one of said members, 10 and means regulating such adjustment to limit the pressure of contact.

11. A suction-roll having provision for maintaining contact between the suction-box and interior surface of the cylinder at a 15 limited degree of pressure by relative longitudinal adjustment between the box and cylinder on a line inclined to the line of contact.

12. A suction-roll wherein relative longitudinal movement is allowed between the suction-box and cylinder on a line slanting to the line of contact between the box and interior surface of the cylinder, and having stop-means limiting such movement in a 25 direction to increase the pressure of contact, to prevent locking of the box to the cylinder under the attractive force of suction.

13. A suction-roll having its cylinder and suction-box arranged for longitudinal adjustment of one of them and having provision whereby such longitudinal adjustment effects a relative radial adjustment, and adjusting means operating on the adjustable member and thereby regulating the bearing 35 pressure between the suction-box and interior surface of the cylinder.

14. A suction-roll wherein relative longitudinal adjustment is allowed between the suction-box and cylinder and having provision whereby relative radial adjustment 40 results, and means controlling such adjustment to regulate the pressure of contact between the box and interior surface of the cylinder.

45 15. A suction-roll wherein relative longitudinal movement is allowed between the suction-box and cylinder, the line of movement being inclined to or non-parallel with the interior surface of the cylinder, a spring 50 forcing the box and cylinder in contact, and stop-means limiting the relative movement under the force of said spring.

16. A suction-roll wherein the pressure of contact between the suction-box and interior 55 surface of the cylinder is controlled by relative longitudinal adjustment between said members, and means for regulating such adjustment comprising a single adjusting instrumentality located at one end of the cylinder.

60 17. In a suction-roll, the combination of the cylinder and suction-box therein, one longitudinally-adjustable relatively for regulating the pressure of contact between the 65 box and interior surface of the cylinder, cyl-

inder-bearings, and heads rigid therewith, the box being slidably-fitted to said heads for guiding the longitudinal movement.

18. In a suction-roll, the combination of the cylinder and suction-box therein, cylinder-supports in which the cylinder has its bearings, box-supports carried by and rigid with the cylinder-supports, the box and the cylinder being arranged so that one is longitudinally-adjustable relative to the other for 75 regulating the pressure of contact therebetween, and the adjustable member being slidably in its supports.

19. In a suction-roll, the combination of the cylinder and suction-box therein, one 80 longitudinally-adjustable relatively for regulating the pressure of contact between the box and interior surface of the cylinder, cylinder-bearings, and heads coaxial therewith and slidably-fitted to the box for guiding the 85 longitudinal movement.

20. In a suction-roll, the combination of the cylinder and suction-box therein, one longitudinally-adjustable relatively for regulating the pressure of contact between the 90 box and interior surface of the cylinder, a spring yieldingly forcing the adjustable member in a direction to preserve the contact, and stop-means limiting the action of said spring.

95 21. In a suction-roll, the combination of the cylinder and suction-box therein, one longitudinally-adjustable relatively for regulating the pressure of contact between the box and interior surface of the cylinder, supports for the box and cylinder with relation to which the adjustable member is movable, means operating between a support and the adjustable member for forcing said member in a direction to preserve the contact, and 100 means operating between a support and said adjustable member for limiting the pressure of such contact.

105 22. In a suction-roll, the combination of the cylinder and suction-box therein, one longitudinally-adjustable relatively for regulating the pressure of contact between the box and interior surface of the cylinder, supports for the box and cylinder with relation to which the adjustable member is movable, 110 and an adjusting instrumentality operating between a support and the movable member for regulating the longitudinal adjustment.

115 23. In a suction-roll, the combination of the cylinder and suction-box therein with provision for maintaining air-tight contact therebetween by forcing one endwise relative to the other, supports provided with cylinder bearings, and an adjusting instrumentality operating between a support and the 120 box to limit the pressure of such contact.

125 24. In a suction-roll, the combination of the cylinder and suction-box therein, one longitudinally-adjustable for regulating the pressure of contact therebetween, non-rotat- 130

ing members or heads concentric with the cylinder and relative to which the box is movable, and an adjusting screw extending through a head and connecting with the box 5 for regulating the adjustment.

25. In a suction-roll, the combination of the cylinder and suction-box therein, one longitudinally-adjustable relatively, the cylinder having a tapered interior surface and 10 the contacting face of the box being correspondingly inclined, supports for the cylinder and box relative to which one is 15 slideable, and an adjusting instrumentality operating between such slideable member and a support.

26. In a suction-roll, the combination of the cylinder and suction-box therein, one longitudinally-adjustable relatively, the cylinder having a tapered interior surface and 20 the contacting face of the box being corre-

spondingly inclined, cylinder-bearings, heads rigid therewith providing guides with the box, and an adjusting instrumentality operating between a head and the box.

27. In a suction-roll, the combination of the cylinder and suction-box therein, one member being longitudinally-adjustable for regulating the pressure of contact between the box and interior surface of the cylinder, cylinder-bearings, and box-supports rigid therewith and angularly-adjustable about the axis of the cylinder for setting the box at different angular positions in the cylinder. 25 30

In testimony whereof I affix my signature, 35 in presence of two witnesses.

WILLIAM H. MILLSPAUGH.
